UNITED STATES PATENT OFFICE.

HENRY H. SKEVINGTON, WILLIAM L. WHITEHEAD, AND WILLIAM HARRIS SELTZER, OF PHILADELPHIA, PENNSYLVANIA.

SINGEING-MACHINE.

No. 821,676.

Specification of Letters Patent.

Patented May 29, 1906.

Application filed August 26, 1904. Serial No. 222,255.

To all whom it may concern:

Be it known that we, HENRY H. SKEVINGTON, WILLIAM L. WHITEHEAD, and WILLIAM HARRIS SELTZER, citizens of the United States, 5 residing in the city and county of Philadelphia, and State of Pennsylvania, have invented new and useful Improvements in Singeing-Machines, of which the following is a specification.

Our invention relates to singeing-machines used for removing the fiber fuzz, lint, or nap from the surface of knit or other fabric, to produce a lisle or silk-like smooth finish on the goods to be treated in a manner well known by the profession for the last fifty years.

The object of our invention is to provide a machine by which better results are obtained, more goods turned out in a given time than heretofore, and in which the treated goods are delivered in one compartment, while the supports or boards on which the goods were secured before treatment are deposited in another compartment.

Our invention consists of a machine comprising a hopper or receptacle into which the goods stretched on boards are deposited, an automatic feeding mechanism, sets of feed-rollers, sets of burner-tubes adjacent to said feed-rollers, a set of rotary brushes to remove the burned-off matter before the final singeing, a deposit-apron for bringing the boards with goods between feed-rollers, a stripper located in the path of the said boards and adapted to strip the goods from the supporting form or board, and separate receptacles for the goods and the boards, and our invention further consists of the improvements hereinafter described, and pointed out 40 in the claims.

Our invention will be more fully understood, taken in connection with the accompanying drawings, forming part hereof, and in which—

Figure 1 is a front elevation of our improved singeing-machine. Fig. 2 is a longitudinal section of our machine, showing at the left-hand end the hopper and the automatic feeding mechanism, one set of feed-rollers, a set of burner-tubes, a set of rotary brushes, a secondary set of feed-rollers, another set of burner-tubes, a set of delivery-rollers, an adjustable bumper, a deposit-apron for receiving and feeding a form with goods

to and through a stripper, a receptacle for the treated goods, and a receptacle for the supporting boards or forms. Fig. 3 is a rear elevation of the machine, showing the driving mechanism for the automatic feed, the driving-gears and belting for the various feed-rollers and canvas apron, and also the adjustable bumper. Fig. 4 is a top view of the improved singeing-machine. Fig. 5 is a cross-section on the line 5-5 of Fig. 4. Figs. 6 and 7 show details of the burner-tubes. Fig. 8 is a front view of our improved stripper. Fig. 9 is an end view of said stripper. Fig. 10 is a section on line 10-10 of Fig. 8, showing the stripper in operation. Fig. 11 is a detail view showing one set of feed-rollers, a pair of brushes, and a set of burner-tubes; and Fig. 12 is a side view of the feed-roller bearings.

Referring now to the drawings for a further description of our invention, A is the framework of our machine on which the various devices, &c., are supported and journaled. At the left-hand end of Figs. 1, 2, and 4, and at the right-hand end of Fig. 3 is shown the feeding-table B with receptacle or hopper b, in which forms or boards for supporting the goods are deposited. It may here be stated that goods to be singed are stretched over or otherwise secured to boards or forms, and for convenience stockings on stocking-boards are shown throughout the drawings, although drawers and undershirts or combination-suits of knit or other goods may be treated in a similar manner on one or both sides of such boards. Since stockings and stocking-boards have been shown in the drawings, reference will be had to such only, although, as stated before, other goods of larger or smaller size may just as well be treated in the same kind of machine.

In the feeding-table B, extending under the receptacle or hopper b, are provided grooves b³, in which feed-bars b' and b' are reciprocated to feed the stocking-boards from the receptacle or hopper b into the center of the machine, while a lever e causes the stocking-board in the center of the machine to enter between the feed-rollers d and d'. The feed-bars b' are supported in grooves b³ of the table B and are provided with projections b⁴, Fig. 5, adapted to engage the lowest stocking-board in the receptacle or hopper b and force it toward the center of the table, as

shown in dotted lines in Fig. 4. These feed-bars b' are provided with lugs b^5 , having slots b^6 , in which pins secured to the arms b^7 operate to actuate the said bars b' . The arms b^7 are secured to a shaft b^8 , Figs. 2, 3, and 5, journaled to the machine-frame A, and the shaft with the arms is reciprocated by a crank b^9 secured to the shaft b^8 , a connecting-rod b^{10} , and a crank b^{11} on the shaft b^{12} . The upper end of the rod b^{10} is provided with a universal joint to prevent twisting of the rod b^{10} on account of the arrangement of the shafts b^8 and b^{12} , which are located at right angles to each other. The shaft b^{12} is rotated from the main shaft C by the pulleys c^1 , c^2 , c^3 , and c^5 and the belts c' and c^4 , Figs. 2, 3, and 5. The projections b^4 , Fig. 5, of the bars b' are tapering and are highest at the outer end, so that while the lowermost board is pushed out of the receptacle or hopper b the stack of boards above the same is lifted in order to clear the lower board from the stack as quickly as possible.

In the side b^{13} of the receptacle or hopper b is cut a slot b^{14} to provide an exit for the boards or forms. To advance the same toward and between the set of feed-rollers d d' , a lever e is trunnioned in bearings e' on the machine-frame A and operated from a cam e^2 on the shaft b^{12} , Figs. 2 and 5. The cam e^2 and crank b^{11} are set on the shaft b^{12} in such a way that the lever e is operated upon while the feed-bars b' move outwardly in the direction of the arrow, Fig. 5, so that the board pushed out from the receptacle or hopper b by the bars b' is immediately thereafter pushed between the feed-rollers d d' by the upper end of the lever e , which may be provided with a cross-piece e^3 , as shown in Fig. 4, to insure the proper engagement of the upper end of the lever e with the stocking-board.

Back of the set of feed-rollers d d' is provided a set of burner-tubes f and f' for the purpose of singeing the fiber fuzz or lint from the surface of the knit goods stretched over the stocking or other board and forwarded through the feed-rollers d d' . These burner-tubes f and f' , for which a separate application will be filed, may be of any preferred construction to suit various requirements, and although we do not claim the burner-tubes and adjuncts shown in the drawings in this application we deem it desirable to describe the same, because of the satisfactory results we have obtained with them. One of the burner-tubes f is shown in Figs. 6 and 7 in detail. The air-supply pipe f^1 is provided with a valve f^4 and an elbow f^2 , in which a gas-supply pipe f^3 , extending beyond the elbow f^2 , is arranged. A valve f^6 regulates the gas-supply into the burner-tube, and the latter is supplied with a series of small nozzles f^7 , through which the gas and air issue, and to produce a continuous line of even flames from the said nozzles a groove f^8 is cut,

connecting the said nozzles, as particularly shown in Fig. 7. The tube f is arranged so that the flame issuing from the nozzles f^7 and groove f^8 is directed at a slight angle from the vertical downward toward the top 70 of the stocking-board, and the lower tube f' is set in advance of the upper tube f , so that the flames issuing in an upward direction therefrom do not injure the upper tube f when a board has passed the said tubes f 75 and f' . From the burner-tubes f and f' the board with the stocking passes between the rotary brushes g and g' , operating in a direction opposite to that of the feed-rollers d and d' and designed to remove the singed and 80 other matter adhering to the surface of the stocking. The gearing and driving mechanism for these brushes, feed-rollers, &c., will be described hereinafter.

Just back of the brushes g and g' are journaled three feed-rollers h , h' , and h^2 , the two upper rollers h and h' of which are adapted to receive the board from the brushes g and g' and feed it farther on through another set of burner-tubes i^9 and i^{10} , arranged in the same 90 manner as the tubes f and f' and adapted to give a finish to the outer surface of the stocking. From the feed-rollers h and h' the stocking-boards may be fed into and through another set of feed-rollers k and k' to forward 95 the same onto a table or movable apron i^2 , or the upper roller k may be omitted and the stocking-board allowed to be carried along by its momentum obtained from the feed-rollers h and h' , the movement of the board 100 being in such case assisted by the roller k' .

On an extension a of the frame A are journaled two rollers i and i' , over which an endless apron i^2 is mounted, the upper surface of this apron traveling in the direction indicated 105 by an arrow in Fig. 2 and adapted to feed the stocking-board deposited on the said apron i^2 toward and between the feed-rollers k' and k^2 for a purpose to be presently described.

On the extension a of the machine-frame A may be arranged in any suitable manner an adjustable bumper i^3 for the purpose of checking the travel of the stocking-board beyond the feed-rollers k and k' , and as long and short stockings are treated by the machine it is desirable to have an adjustable bumper. This bumper may be of any desired design and shape. In the drawings, however, we have shown a bumper of a simple construction comprising a bracket i^4 at each side of the extension a . These brackets i^4 , with braces, are held in holes i^5 of a series provided in the extension a and may be secured thereto by thumb-nuts i^6 , Figs. 1, 2, 3, and 4. Between the brackets i^4 and held thereby are two rods i^7 , Figs. 2 and 4, over which canvas or other cloth is fastened to form the bumper i^3 .

From Fig. 4 it is seen that the toe end of the stocking and stocking-board enters all 130 the feed-rollers first to prevent the overlap-

ping or partial stripping of the stocking from the board; but in order to strip the stocking from the board after it leaves the feed-rollers k and k' it is brought between the feed-rollers k' and k^2 by the apron i^2 , as before described, and the stocking-board with stocking is fed by the rollers k' and k^2 toward a stripper S , adapted to remove the stocking from the board and deposit the former into a basket s' . Fig. 2. This stripper S consists of two spring-connected flaps s^2 and s^3 , Figs. 8, 9, and 10, which are pivoted at s^4 in the brackets s^5 of the machine-frame A . At the backs of these flaps s^2 and s^3 are provided pins s^6 , and a spring s^7 is connected to the free ends of said pins, so that the flaps are held in normal position, as shown in Fig. 9, where the back stops s^8 rest against the edge of one of the brackets s^5 . The pivots s^4 of the flaps s^2 and s^3 are not on a vertical line, for the reason that the stocking on one side of the board should be stripped somewhat in advance of the other side in order to facilitate the operation of stripping.

In stripping the stocking from the board the latter is drawn between the flaps s^2 and s^3 , Figs. 2 and 10, by the action of the feed-rollers $k', k^2, h',$ and h^2 and the flaps, owing to the resiliency attained by the spring s^7 , adjust themselves to the thickness of the board and remove therefrom the stocking without injuring the latter in the least and the stocking is deposited in the basket s' . The board travels on over the idle roller s^8 and is guided by a chute s^9 into a receptacle s^{10} , the sloping bottom s^{11} of which causes the boards to be delivered at the side of the machine, where they may be picked up and again provided with stockings for treatment.

The machine is driven from the main shaft C , which imparts rotary motion to the feed-roller d' , Fig. 3, by the belt c^6 , the rollers d and d' being provided with gear-wheels c^7 and c^8 , Fig. 1. The roller h' is driven from the roller d' by means of pulleys and belt c^9 , Fig. 4, and as the rollers h and h' and h^2 are geared to each other, Figs. 1 and 4, they are driven in the desired direction. The roller k' receives motion through the pulleys and belt c^{10} from the roller h' , and as the rollers $k, k',$ and k^2 are also geared to each other, Figs. 1 and 4, they operate to move the stocking-board in the direction required. The apron i^2 is actuated by the roller i , which is geared to the feed-roller k' by means of the gear-wheels c^{11} , Figs. 3 and 4, while the brush g is driven by the straight belt c^{12} and the brush g' by the crossed belt c^{13} from the pulleys on the shaft C , Figs. 1 and 4.

To vary the speed of the machine, cone-pulleys c^{14} and c^{15} are provided on the main shaft C and the shaft of the roller d' , as shown in Figs. 3 and 4.

All of the top rollers $d, h,$ and k and the bottom rollers h^2 and k^2 are journaled in sliding bearing-blocks m , Figs. 11 and 12, and springs m' are interposed between said bearing-blocks m and removable caps m^2 , so that the said rollers will bear upon the rollers $d', h',$ and k' or the board passing between them with an appropriate pressure and adjust themselves to various thicknesses of board. This pressure may be adjusted by the screw-bolts m^3 , threaded in the caps m^2 and bearing upon washers m^4 at the ends of the springs m' .

To produce a blue flame of equal size the entire length of the slot f^8 in the burner-tube, the gas is mixed with air, which is preferably taken from some place or room outside of the room where the machine is located or from the outside of the building, as the air contained in the room is generally laden with yarn-fuzz, and other matter, which would soon clog the extremely fine orifices f^7 .

The gas entering through the small pipe f^5 into the burner-tube f mixes with the air admitted into the burner-tube f under pressure, which latter may be obtained in various ways. The most reliable and preferable means is to provide a blower p of suitable construction on the machine-frame A and connect the same to a large pipe p' , closed at p^2 to form a sort of a reservoir. The air is taken in through the pipe p^3 and the rotary blower p operated from the main shaft C by pulleys, and the belt p^4 keeps the air in the reservoir p' under a certain pressure so long as the machine is in operation.

It will be understood by those skilled in the art to which our invention relates that modification may be made in the arrangement of parts and devices constituting our singeing-machine without departing from the spirit of our invention.

Having thus described the nature and objects of our invention, what we claim as new, and desire to secure by Letters Patent, is—

1. In a singeing-machine having one or more sets of feed-rollers and burner-tubes, the combination of a feed-hopper, a feeding-table, an automatic feeding device for feeding fabric-supporting forms from the hopper onto said feeding-table and into the center of the machine, and means for automatically feeding the said forms between the said feeding-rollers, substantially as and for the purposes set forth.
2. In a singeing-machine having one or more sets of feed-rollers and burner-tubes, the combination of a feed-hopper, a feeding-table and an automatic feeding device for feeding fabric-supporting forms from the feed-hopper to and between the said feed-rollers, said feeding device comprising two sliding bars extending partly above the feeding-table and adapted to remove from the said hopper the lowermost of the forms contained therein and deposit the same in the center of the machine, a lever journaled in the frame of the machine and adapted to

push the fabric-supporting form between the said feed-rollers, and means for actuating said feeding device from the main shaft of the machine, substantially as and for the purposes set forth.

3. In a singeing-machine having one or more sets of feed-rollers and burner-tubes, the combination of a feed-hopper, a feeding-table and an automatic feeding device for feeding fabric-supporting forms from the hopper into the center of the machine and between said feed-rollers at one end of the machine, a movable apron at the other end of the machine, an adjustable bumper beyond said apron, a set of return-feed-rollers adjacent to said apron adapted to move the said fabric-supporting forms toward the hopper end of the machine, substantially as and for the purposes set forth.
- 20 4. In a singeing-machine having one or more sets of feed-rollers and burner-tubes, the combination of a feed-hopper, a feeding-table, an automatic feeding device for feeding fabric-supporting forms from the hopper into the center of the machine and between said feed-rollers at one end of the machine, a movable apron at the other end of the machine to receive the said forms, a set of return-feed-rollers, said apron adapted to bring 25 the said forms between the said return-feed-rollers; substantially as and for the purposes set forth.
- 30 5. In a singeing-machine having one or more sets of feed-rollers, burner-tubes and means for automatically feeding fabric-supporting forms into the center of the machine and between said feed-rollers and burner-tubes, in combination with a traveling apron adapted to receive the said forms, and a stripper comprising a frame and two resilient flaps adapted to remove the fabric from the supporting-forms, substantially as and for the purposes set forth.
- 35 6. In a singeing-machine, having one or more sets of feed-rollers, burner-tubes and means for automatically feeding fabric-supporting forms into the center of the machine and between said feed-rollers and burner-tubes, in combination with a traveling apron, an adjustable bumper, and a stripper, the latter comprising a frame and two resilient flaps hinged to said frame and adapted to remove the fabric from the supporting-forms, while the forms are being advanced by the said 40 feed-rollers, substantially as and for the purposes set forth.
- 45 7. In a singeing-machine, the combination of feed-rollers and burner-tubes, said rollers adapted to feed fabric-supporting forms between said burner-tubes, with a traveling apron, a bumper, return-feed rollers and a

stripper, the latter comprising a frame and two resilient flaps pivoted to said frame and adapted to remove fabric from a supporting-form while the form is moved along by the 55 said return-feed rollers, substantially as and for the purposes set forth.

8. In a singeing-machine the combination of feed-rollers, and burner-tubes, said rollers adapted to feed fabric-supporting forms between said burner-tubes, means for automatically feeding fabric-supporting forms into the center of the machine and between said feed-rollers, of an adjustable bumper, a traveling apron, return-feed rollers, a stripper, a 70 receptacle for the stripped fabric and a receptacle for the supporting-forms, substantially as and for the purposes set forth.

9. In a singeing-machine the combination of feeding mechanism with a stripper for removing the fabric from a form after the same has been treated by the machine, said stripper comprising a frame secured to the machine-frame, a flap pivoted to the said frame above the path of the said form, a flap pivoted to the frame below the path of the said form, pins extending from the rear of the flaps, a helical spring attached to said pins and a back stop for each of the flaps impinging on the frame of the stripper, substantially 85 as and for the purposes set forth.

10. In a singeing-machine the combination of feeding mechanism with a stripper for removing the treated fabric from a form, said stripper comprising a frame attached to the machine, two flaps pivoted in said frame, back stops on said flaps to impinge on the frame and a spring or springs to hold the said flaps in normal position, substantially as and for the purposes set forth.

11. In a singeing-machine the combination of feeding mechanism with a stripper for removing the treated fabric from a form, said stripper comprising a frame, a flap above the path of the form, a flap below the path of the form, the latter having its pivots outside of a vertical line through the pivots of the upper flap, means for limiting the movement of the said flaps around their pivots and a spring or springs adapted to hold the flaps in normal position, substantially as and for the purposes set forth.

In witness whereof we have hereunto set our hands in the presence of the subscribing witnesses.
